PUMP

John Calling, Chicago, Ill., assignor to International Harvester Company, a corporation of New Jersey

Application August 24, 1936, Serial No. 97,495

9 Claims. (Cl. 230—79)

This invention relates to improvements in gas moving devices. More particularly, it relates to such a device particularly adapted for air compressors or vacuum pumps.

An example of such a device is found in the Nash Patent 1,091,529, March 31, 1914, which shows an impeller type of pump in which the spaces between the impeller blades form buckets. By rotation of the impeller the liquid is thrown outwardly from the impeller into an enlarged portion of the impeller casing, thereby producing a suction. Due to the shape of the casing the liquid moves around a smooth wall thereof and is again picked up by the impeller blades, thereby filling the buckets formed by the blades and discharging the gas therein. This type of pump has been found to have a particular utility in combination with apparatus requiring delivery of air for a predetermined length of time, as disclosed and claimed in assignee's application relating to Milk refrigerating cabinets, which resulted in Patent No. 2,077,871, April 20, 1937. As disclosed in said application, a predetermined amount of liquid may be supplied to the impeller chamber, where- 25 by the flow of air is stopped when the liquid has disappeared due to agitation and entrainment of the liquid by the air or gas being pumped.

The present invention relates to an improvement in the means for supplying liquid to a pump of the liquid seal impeller type. More specifically the invention relates to such a pump in which liquid may be added after the pump is in operation without the use of valves of any type.

These objects and others which will be apparent from the description which follows are attained by a construction such as disclosed in the drawings, in which:

Figure 1 is an end elevation of the assembled pump;

Figure 2 is a substantially vertical section taken on the line 2—2 of Figure 1, also on the line 2—2 of the conduit plate shown in Figure 3;

Figure 3 is an elevation of the outer side of the conduit plate;

Figure 4 is an elevation of the front side of the conduit plate;

Figure 5 is an elevation of the open side of the main casing with the impeller shown in position and with the liquid sealing medium indicated by broken lines; and,

Figure 6 is an elevation of the closed side of the impeller.

The pump illustrated consists essentially of four principal elements. The main casing 10 is se- 55 cured by brackets 11 to an electric motor 12, a

portion of which is shown in Figure 2. A conduit plate 13 is fitted over the open side of the main casing 10, being secured thereto by a plurality of cap-screws which also secure a cover plate 14 in position over the outer face of the conduit plate. 5 An impeller 15 is fixed on the motor shaft 16 for rotation therewith. Said impeller is rotatably mounted in the main casing in an impeller chamber 17. With these main elements being briefly described, their relation will be described in detail. 10

The impeller 15 is provided with a hub 18, which is slidably fitted onto an extension of the motor shaft 16. Said hub abuts a radial flange 19 formed on a sleeve 20 spaced from the motor shaft. Said 15 sleeve is provided with a conical deflector 21 at the outer end to provide a liquid throwing means. An annular member 22 is fitted on the motor shaft 16 abutting a stop 16' formed thereon. Said member is provided with ridges 22' for throwing 20 liquid outwardly during rotation of the motor, thereby preventing liquid from reaching the bearings of the motor. The annular member 22, the sleeve 20, and the hub 18 of the impeller are secured on the motor shaft by a cap-screw 23. 25

From the outer end of the hub member 18, a radial flange 24 extends outwardly to connect the hub with a cylindrical flange 25 which forms the base for spirally arranged, circumferentially spaced impeller blades 26. At the outer ends the 30 spaces between the impeller blades, which may be termed as pockets, are open on the radial face of the impeller. At the other end the spaces are sealed by a radial flange 27. At its periphery said flange is provided with an annular lip 28 35 which is utilized, as will be hereinafter described, to reduce the amount of liquid which by-passes the impeller on the inner face.

The main casing 10 is provided, as previously stated, with an impeller chamber 17. Said chamber is substantially cylindrical at each end with the two ends spaced apart and joined by flattened side walls. A construction is thereby formed which might be termed as somewhat elliptical in shape, having a smooth inner contour, around 40 which fluid may readily flow with a minimum of resistance. As best shown in Figure 5, the impeller chamber is arranged with its larger dimension at an angle with respect to vertical of substantially 45 degrees. 50

Adjacent the motor, the casing 10 is formed with an opening 29, through which the motor shaft extends. It will be noted that there is no contact between the motor shaft and the parts carried thereby with the casing or parts mounted 55

thereon. At the end through which the motor shaft extends, the casing 10 is provided with a cylindrical recess 30 in which a sealing sleeve 31 is tightly fitted. Said sleeve carries a radial flange which terminates closely adjacent the sleeve 20. Any liquid which escapes around the impeller must pass between the edge of said flange and the sleeve 20. Said liquid then is thrown outwardly by the conical edge portion 21 of the sleeve 20 into the cylindrical recess 30. A drain conduit 32 communicates with the cylindrical recess 30 through an opening formed in the sleeve 31. Said drain conduit extends downwardly and across the bottom of the casing communicating 15 with the air inlet means to the casing, as will be hereinafter described.

It will be noted that the inner wall of the impeller chamber adjacent the impeller lies closely adjacent the impeller and is provided with 20 a shoulder 33, which overhangs the periphery of the flange 27. By this construction a minimum amount of liquid escapes past the impeller without an actual contacting seal. The liquid which escapes is drawn back into the system 25 through the drain 32. An important advantage is attained by this construction by reason of the fact that no bearing surface is provided, and, therefore, no lubrication is required. There is also an advantage in the fact that, when the impeller 30 is running idle,—that is without a supply of liquid,—there is no bearing friction present and no resulting load therefrom on the motor.

The conduit plate 13, as shown in Figures 3 and 4, is provided with an inlet conduit 34, which 35 terminates at its lower end in a tubular extension 35 on which a flexible hose may be fitted. Said inlet conduit communicates with two branch inlet conduits 36 extending through the plate. The outlet ends of said conduits are diametrically 40 opposite each other and are located with respect to the impeller as shown by dotted lines in Figure 5. The conduits terminate at the open ends of the pockets formed by the impeller blades adjacent the bottom walls thereof, which are formed 45 by the flange 25. As the liquid is thrown from the pockets air is drawn in through the inlet conduits 36.

It will be noted in Figure 2 that at its point of communication with the conduit plate, the 50 extension conduit 35 is flattened and restricted in cross section. A nozzle effect is thereby obtained with an expanding stream of air. Liquid from the drain conduit, which communicates with the inlet conduit at this point, is entrained 55 and carried with the inlet air back into the impeller chamber.

A small drain opening 32' is formed in the conduit plate 13. Said opening forms a communication between the impeller chamber 17 and 60 the inlet conduit 34 and provides a drain for the chamber when the pump is not in operation.

For supplying liquid to the pump to initiate 65 operation, a filling conduit 37 connecting with the lower branch inlet conduit 35 extends upwardly through the conduit plate and communicates with a filling conduit 38 formed in the casing 10. Said conduit communicates with an enlarged filler neck 39 covered by a cap 40. Said cap closely fits over the top of the filling neck and 70 is pivoted for swinging upwardly when water is supplied.

It will be understood that suction produced by the impeller in the inlet conduits will act to maintain the cover 40 in a closed position. Such air 75 as may be drawn in around the filler cap does

not impair operation of the pump. By means of a filler arrangement of this type liquid may be added while the motor and impeller are in operation. This is one of the principal points of improvement over the pump disclosed in the application previously referred to. 5

As the impeller rotates, liquid, which had been previously thrown out to the enlarged ends of the impeller casing, moves around the wall thereof and is engaged by the impeller blades thereby 10 filling the pockets thereof. The displacement of air brought about by this action results in the movement of air through the outlet openings 41, which have been shown in Figure 5 in dotted lines to indicate their position, although the conduit plate which carries them is not shown in this figure. 15

The outlet openings 41 communicate with outlet conduits 42 leading upwardly and merging into an outlet conduit 43, which discharges at a 20 high point in the casing into a liquid chamber 44 formed in the upper portion of the casing above the impeller chamber 17. At the high speed of an electric motor considerable agitation is 25 produced in the impeller chamber with the result that a considerable percentage of the liquid therein escapes with the air discharged therefrom. Mixture of air and water is discharged into the liquid chamber with a substantial percentage 30 of the water separating therefrom. A certain amount of the water entrained as a fine mist by the air is discharged from the upper end of the water chamber through an opening communicating with a discharge conduit 45 formed in the conduit plate 13. Said conduit, as best shown in 35 Figure 3, extends to the lower end of the cover plate communicating with an outlet extension 46.

It will be understood that, when the device, as described, is put into operation, liquid poured into the filler neck 39 passes into the impeller chamber, filling said chamber completely except for the amount displaced by the impeller blades at each 40 end of the chamber. The liquid supplied in excess of this amount is forced by the impeller through the outlet conduits into the water chamber 44. Said chamber is so constructed and positioned that all of the liquid therein drains to the low point at one side, which is in communication, by means of a conduit 47 formed in the conduit plate, with the inlet conduit 34. To regulate the 50 flow of water through said conduit, a bore 48 extending through the cover plate and into the conduit plate passes through a restricted portion of the conduit 47. A metering pin 49 is fitted in said bore, being secured therein by a cap-screw 50 on 55 the cover plate. Said metering pin is provided with a transverse metering opening 51 which determines the rate of liquid flow passing through the conduit 47 into the inlet 34.

In the operation of the device, water from the 60 chamber 44 is continually returned to the impeller chamber, thereby replenishing a substantial portion of the amount carried through the outlet conduits. However, as an appreciable amount is carried over through the discharge conduits, the water in the chamber 44 is gradually depleted during 65 operation. When the entire supply has been depleted, the amount in the impeller chamber is soon reduced until it is no longer sufficient to maintain a seal over the impeller blades and to 70 provide for displacing air in the pockets formed by said blades. The suction is then broken at the inlet side of the device with the result that the remaining liquid drains downwardly through the inlet extension 35. By such a construction, the 75

operation of which has been described in connection with the description, a pump is provided which forces air for a predetermined length of time. After the seal has been broken, air is no longer forced through the discharge conduit. A particular advantage of this type of pump for an operation of this type is that, when effective operation of the pump ceases, there is no friction or wear. The motor, which may be operating other parts, such as the compressor of a cooling system, may continue to run without any appreciable load, due to the impeller, which is merely fanning the air around the impeller chamber and with no resistance due to friction of pump bearings.

15 It is to be understood that applicant has shown only a preferred embodiment of his improvements in the particular type of air moving device disclosed, and that he claims as his invention all modifications falling within the scope of the appended claims.

What is claimed is:

1. An air pump comprising a casing formed with an impeller chamber, an impeller formed with circumferentially spaced radially projecting blades rotatably mounted in said chamber, said chamber being formed with an enlarged portion of a smooth contour adjacent one section of the impeller, an inlet conduit communicating with said chamber at the enlarged portion adjacent the inner ends of the impeller blades, a water chamber formed in the casing with its lower portion in gravity fed communication with the inlet conduit, an air outlet conduit communicating with the impeller chamber adjacent the impeller blades 35 in advance of the enlarged portion in the direction of rotation of the impeller and with the top of the water chamber, a water supply conduit extending downwardly from the top of the casing and communicating directly with the inlet conduit, and a discharge conduit communicating with the top of the water chamber.

2. An air pump comprising a casing formed with an impeller chamber, an impeller formed with circumferentially spaced radially projecting blades rotatably mounted in said chamber, said chamber being formed with an enlarged portion of a smooth contour adjacent one section of the impeller, an inlet conduit communicating with said chamber at the enlarged portion adjacent the inner ends of the impeller blades, a water chamber formed in the casing with its lower portion in gravity fed communication with the inlet conduit, means for metering the flow of water from said chamber to said conduit, an air outlet conduit communicating with the impeller chamber adjacent the impeller blades in advance of the enlarged portion in the direction of rotation of the impeller and with the top of the water chamber, a water supply conduit extending downwardly from the top of the casing and communicating directly with the inlet conduit, and a discharge conduit communicating with the top of the water chamber.

3. An air pump comprising a casing formed with an impeller chamber, an impeller formed with circumferentially spaced radially projecting blades rotatably mounted in said chamber, said chamber being formed with an enlarged portion of a smooth contour adjacent one section 65 of the impeller, an inlet conduit communicating with said chamber at the enlarged portion adjacent the inner ends of the impeller blades, a water chamber formed in the casing with its lower portion in gravity fed communication with the inlet conduit, an air outlet conduit communicating with the top of the water chamber.

cating with the impeller chamber adjacent the impeller blades in advance of the enlarged portion in the direction of rotation of the impeller and with the top of the water chamber, a water supply conduit extending downwardly from the top of the casing and communicating with the inlet conduit, a closure for said conduit fitted to be maintained in closed position by suction during operation of the pump, and a discharge conduit communicating directly with the top of the water chamber.

4. An air pump comprising a casing open at one side formed with an impeller chamber, an impeller formed with circumferentially spaced radially projecting blades rotatably mounted in said chamber, said chamber being formed with an enlarged portion of a smooth contour adjacent one section of the impeller, a cover plate fitted over said casing, an inlet conduit formed in said plate communicating with said chamber at the enlarged portion adjacent the inner ends of the impeller blades, a water chamber formed in the casing with its lower portion in gravity fed communication with the inlet conduit, an air outlet conduit formed in the cover plate communicating with the impeller chamber adjacent the impeller blades in advance of the enlarged portion in the direction of rotation of the impeller and with the top of the water chamber, a water supply conduit formed in the cover plate extending downwardly from the top of the casing and communicating with the inlet conduit, and a discharge conduit formed in the cover plate communicating with the top of the water chamber.

5. An air pump comprising a casing open at one side formed with an impeller chamber, an impeller formed with circumferentially spaced radially projecting blades rotatably mounted in said chamber, said chamber being formed with an enlarged portion of a smooth contour adjacent one section of the impeller, a cover plate fitted over said casing, an inlet conduit formed in said plate communicating with the said chamber at the enlarged portion adjacent the inner ends of the impeller blades, a water chamber formed in the casing with its lower portion in gravity fed communication with the inlet conduit, means carried by the cover plate for metering the flow of water from said chamber to said conduit, an air outlet conduit formed with the cover plate communicating with the impeller chamber adjacent the impeller blades in advance of the enlarged portion in the direction of rotation of the impeller and with the top of the water chamber, a water supply conduit formed in the cover plate extending downwardly from the top of the casing and communicating with the inlet conduit, and a discharge conduit formed in the cover plate communicating with the top of the water chamber.

6. In an air pump having a casing formed with an impeller chamber, an impeller formed with circumferentially spaced radially projecting blades rotatably mounted in said chamber, said chamber being formed with an enlarged portion of a smooth contour adjacent one section of the impeller, an inlet conduit communicating with said chamber adjacent the inner ends of the impeller blades, said inlet being located at the enlarged portion of the impeller chamber, and an air outlet opening formed in the casing communicating therewith in advance of the enlarged portion of the chamber in the direction of rotation of the impeller and in combination therewith, a water sup-

ply conduit extending downwardly from the top of the casing and communicating with the air inlet whereby water may be supplied directly thereto, a water chamber formed in the casing with its lower portion in communication with the air inlet, said air outlet conduit communicating with the water chamber above the normal liquid level therein, and a discharge conduit communicating with the water chamber above the normal liquid level therein.

7. An air pump comprising a casing formed with an impeller chamber, an impeller formed with circumferentially spaced radially projecting blades rotatably mounted in said chamber, said chamber being formed with an enlarged portion of a smooth contour adjacent one section of the impeller, an inlet conduit communicating with said chamber adjacent the inner ends of the impeller blades, said inlet being located at the enlarged portion of the impeller chamber, an air outlet opening formed in the casing communicating therewith in advance of the enlarged portion of the chamber in the direction of rotation of the impeller, a water supply conduit extending downwardly from the top of the casing and communicating with the air inlet whereby water may be supplied thereto, a water chamber formed in the casing with its lower portion in communication with the air inlet, means for regulating the flow of water from said chamber to said inlet, said air outlet conduit communicating with the water chamber at the upper end thereof above the normal liquid level therein, and a discharge conduit communicating with the water chamber above the normal liquid level therein.

8. In an air pump having a casing formed with an impeller chamber substantially cylindrical at each end and flattened at the sides connecting said ends, an impeller formed with circumferentially spaced radially projecting blades rotatably mounted in said chamber on an axis centrally thereof, said impeller being positioned between the flattened portions of the chamber, said casing being formed with a pair of diametrically positioned inlets communicating with said chamber adjacent the inner ends of the impeller blades, said inlets being located at the cylindrical ends of the im-

peller chamber, a pair of air outlet openings formed in the casing communicating therewith adjacent the flattened sides of the chamber, and an air inlet conduit communicating with said air inlets and in combination therewith; a water supply conduit extending downwardly from the top of the casing and communicating with the air inlets whereby water may be supplied thereto to initiate operation, a water chamber formed in the casing with its lower portion in communication with the air inlet conduit, said air outlet conduits communicating with the water chamber at its upper end above the normal liquid level therein, and a discharge conduit communicating with the water chamber above the normal liquid level therein.

9. An air pump comprising a casing formed with an impeller chamber substantially cylindrical at each end and flattened at the sides connecting said ends, an impeller formed with circumferentially spaced radially projecting blades rotatably mounted in said chamber on an axis centrally thereof, said impeller being positioned between the flattened portions of the chamber, said casing being formed with a pair of diametrically positioned inlets communicating with said chamber adjacent the inner ends of the impeller blades, said inlets being located at the cylindrical ends of the impeller chamber, a pair of air outlet openings formed in the casing communicating therewith adjacent the flattened sides of the chamber, an air inlet conduit communicating with said air inlets, a water supply conduit extending downwardly from the top of the casing and communicating with the air inlets whereby water may be supplied thereto, a water chamber formed in the casing with its lower portion in communication with the air inlet conduit, means for regulating the flow of water from said chamber to said conduit, said air outlet conduits communicating with the water chamber at the upper end thereof above the normal liquid level therein, a discharge conduit communicating with the water chamber above the normal liquid level therein, and a leakage drain conduit communicating with the casing around the impeller shaft and with the air inlet conduit.

JOHN CALLING.
